UNITED STATES PATENT OFFICE.

JAMES SAMUEL BOYD, OF SPRAY, NORTH CAROLINA.

REGISTER.

1,422,024.

Specification of Letters Patent. Patented July 4, 1922.

Application filed September 28, 1920. Serial No. 413,386.

To all whom it may concern:

Be it known that I, JAMES S. BOYD, a citizen of the United States, residing at Spray, in the county of Rockingham and 5 State of North Carolina, have invented new and useful Improvements in Registers, of which the following is a specification.

This invention relates to improvements in looms for weaving blankets and the like, the 10 principal object of the invention being to provide counting means for registering the number of blankets formed by the loom.

Another object of the invention is to provide means whereby the register will be 15 actuated by a roller on the chain of the control cylinder of the loom.

This invention also consists in certain other features of construction and in the combination and arrangement of the several parts, to be hereinafter fully described, 20 illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a side elevation of the head 30 portion of a loom showing my invention in position.

Figure 2 is a plan view of the invention.

Figure 3 is an enlarged face view of the dial and its associated parts.

35 Figure 4 is a view showing certain portions of the invention before being assembled.

Referring to Figure 1, 1 indicates a part of the loom frame in which are journaled the 40 pattern cylinders 2 and a control cylinder 3, these cylinders supporting the chains 2' and 3', which carry the rolls in the usual manner. The cylinders 2 and rolls control the pattern of the body and boarder of the 45 blanket while the cylinder 3 controls the operation of the cylinders 2 so as to throw the body cylinder out of operation and the boarder cylinder into operation and vice versa. The cylinders are actuated by an 50 oscillating member 4 and its pawls 5.

As the parts above referred to and their operation are well known it is not thought necessary to describe them or their operation in detail.

55 In carrying out my invention I secure a supporting standard 6 on the frame 1, the

upper end of the standard being bent twice at right angles, as shown in Figure 4, and its extremity is provided with a hole 7 to receive the cylindrical part of a shaft 8. A 60 dial plate 9 is fastened to the upper part of the standard and this dial plate has a central opening therein which registers with the hole 7. A finger 10 is secured to the squared projecting part of shaft 8 by the 65 nut 11 which engages a screw threaded extension of the shaft. A washer 12 may be placed on the squared part to space the finger from the dial plate. The shaft 8 is provided with a squared part at its rear 70 end ending in a reduced threaded part and this squared part receives the ratchet wheel 13 and a locking disc 14, the wheel and disc being held on the shaft by the nut 15 which engages the reduced threaded part. A locking pawl 16 is secured to the upright and 75 engages the corrugations in the locking disc to insure a step by step movement of the shaft and consequently the finger.

An arm 17 is pivoted to a part of the 80 frame 1 and this arm is adapted to be raised once every complete revolution of the chain 3' of the control cylinder by a roller 18 carried by said chain. The arm 17 carries a pawl 19 which engages the ratchet wheel 85 13, the pawl being held in engagement with said wheel by the spring 20.

The parts are preferably so arranged that when a pair of blankets has been formed the roller 18 will engage the arm 17 and 90 thus cause the pawl to move the shaft and its finger one tooth, the dial plate having the numerals thereon so arranged that this movement of the finger will cause it to pass from one numeral to the next. Thus the 95 register for indicating the number of pieces formed by the loom will indicate that one pair of blankets has been formed.

As it is usually customary to place ten pairs of blankets on the takeup roller the 100 drawing indicates the dial plate with ten numerals. As soon as the register indicates that the ten pairs have been completed the device is reset ready for the next ten pair.

It will of course be understood that if it 105 is desired to register different numbers of pairs this can be done by using a ratchet with a different number of teeth.

It is thought from the foregoing description that the advantages and novel features 110 of my invention will be readily apparent.

I desire it to be understood that I may

make changes in the construction and in the combination and arrangement of the several parts, provided that such changes fall within the scope of the appended claims.

5. What I claim is:—

1. In combination with the control cylinder of a loom, a register and means for operating the same by a part on the chain of said cylinder.
- 10 2. In combination with a control cylinder of a loom, a register for indicating the number of blankets made by the loom, said register including a rotatable shaft, a ratchet thereon, a lever pivoted to a part of the loom, a pawl carried by said lever and engaging the ratchet and a roller on the control cylinder chain for engaging the lever.

3. In combination with a loom and its control cylinder, a supporting standard connected with the loom frame, a shaft rotatably carried by said standard, a dial plate carried by the standard having an opening therein through which the shaft extends, a finger secured to said extended part of the shaft, a ratchet wheel secured to the rear part of the shaft, a locking disc on said shaft, a locking pawl secured to the standard and engaging said disc, a lever pivoted to the loom, a pawl carried thereby and engaging the ratchet wheel and a roller on the chain of the control cylinder for engaging said lever.

20 25 30 In testimony whereof I affix my signature.

JAMES SAMUEL BOYD.
